RAILWAY BRAKING APPARATUS

Herbert L. Bone, Swissvale, and John W. Logan, Jr., Wilkinsburg, Pa., assignors to The Union Switch & Signal Company, Swissvale, Pa., a corporation of Pennsylvania

Application February 17, 1933, Serial No. 657,210

12 Claims. (Cl. 303—20)

Our invention relates to railway braking apparatus, and particularly to braking apparatus of the type comprising wheel engaging braking bars located beside a track rail, and movable toward and away from the rail into braking and non-braking positions. More particularly, our invention relates to apparatus of the type described wherein the braking bars are arranged to be moved to their braking positions by means of one or more fluid pressure operated motors, and to be restored to their non-braking positions by suitable biasing means such as gravity.

Specifically, our invention relates to means for controlling the supply of fluid pressure to, and exhaust of fluid pressure from, the fluid pressure motor or motors of braking apparatus of the type described when the braking apparatus is to be utilized in connection with a duplex pressure fluid distribution system such as is disclosed and claimed in an application for Letters Patent of the United States, Serial No. 639,434, filed by Herbert L. Bone, on October 25, 1932, and one object of our invention is to improve and simplify the control means disclosed in the said Bone application.

Other objects of our invention will appear as the description proceeds.

We will describe two forms of apparatus embodying our invention, and will then point out the novel features thereof in claims.

In the accompanying drawings, Fig. 1 is a diagrammatic view illustrating one form of apparatus embodying our invention. Fig. 2 is a similar view illustrating a modified form of the apparatus shown in Fig. 1.

Similar reference characters refer to similar parts in both views.

Referring to the drawings, the reference character 1 designates one track rail of a stretch of railway track, which track rail, as here shown, is secured to a rail support 2 mounted on an adjacent pair of the usual crossties 3, only one cross-tie being visible in the drawings. Associated with the rail 1 is a car retarder comprising two braking bars A¹ and A² located on opposite sides of the rail. Each of these braking bars comprises, as usual, a brake beam 4 and a brake shoe 5.

The braking bars A¹ and A² are arranged to be moved toward and away from the rail 1 through the medium of a lever 6 which is pivotally mounted at one end on a pivot pin 8 carried by the rail support 2, and a lever 7 which is pivotally mounted intermediate its ends on the pivot pin 8. The lever 6 is inclined upwardly and extends away from the rail 1, and is provided in its upper sur-

face with a groove 6^a which receives the braking bar A¹. The one end 7^a of the lever 7 is likewise inclined upwardly and extends away from the rail 1 at the opposite side of the rail from the lever 6, and the other end 7^b of the lever 7 is inclined downwardly and extends away from the rail 1 below the lever 6. The end 7^a of the lever 7 is provided in its upper surface with a groove 7^c, similar to the groove 6^a in the lever 6, which groove receives the braking bar A². The parts 10 are so arranged and so proportioned that if the outer or free ends of the levers 6 and 7 are moved apart, the braking bars will be moved toward the rail 1 into their effective or braking positions. When the braking bars occupy their braking positions, the brake shoes 5 will engage the opposite side faces of a car wheel traversing rail 1, and will retard the speed of the car. The center of gravity of the lever 6 and braking bar A¹ is considerably to the right of the pivot pin 8 so that this lever will normally tend to rotate in a clockwise direction about the pivot pin. Similarly, the center of gravity of the lever 7 and braking bar A² is to the left of the pivot pin 8, so that this lever will normally tend to rotate in a counter-clockwise direction about the pivot pin. It will be apparent, therefore, that when no force is applied to the free ends of the levers 6 and 7 to move them apart, the free ends of these levers will move toward each other, thereby moving the braking bars to their ineffective or non-braking positions in which they are illustrated in the drawings.

The levers 6 and 7 are arranged to be moved apart to move the braking bars to their braking positions by means of a fluid pressure motor M comprising a cylinder 9 containing a reciprocable piston 10 which drives a piston rod 11. The cylinder 9 is pivotally connected with the free end of the lever 6 by means of trunnions 12 formed on the side of the cylinder and extending through bifurcations 13 formed on the lever 6, while the piston rod 11 is connected at its free end with the free end 7^b of the lever 7 by means of an adjustable eyebolt 14 and a pivot pin 15. Fluid pressure may be admitted to the cylinder 9 between the upper end of the cylinder and the piston 10 through an opening 16 which is threaded to receive a pipe 17. When fluid pressure is admitted to the cylinder 9 through the pipe 17 and opening 16, the piston 10 will be forced downwardly and the cylinder 9 upwardly, thereby separating the levers 6 and 7, and hence moving the braking bars toward their effective or braking positions. It will be obvious that when the braking bars are moved to their braking positions, 55

they will exert a braking force which is proportional to the pressure of the fluid supplied to the cylinder 9.

It should be pointed out that while in the drawings we have shown only one operating unit for the braking bars A¹ and A², in actual practice these braking bars will be provided with a plurality of other similar units, disposed at spaced intervals along the bars, substantially as shown in Patent No. 1,927,201 issued to Herbert L. Bone, on Sept. 19, 1933, for Railway braking apparatus. It should also be pointed out, that as a general rule, the car retarder will consist not only of braking bars associated with one track rail, as shown in the drawings, but also of other similar braking bars associated with the opposite track rail as well, the length of the braking bars associated with both track rails being determined by the speed and the weight of the cars to be retarded, the lengths of the cars, the number of wheels on the cars, etc.

The motor M is controlled by three magnet valves designated by the reference characters V¹, V² and V³, respectively, and each comprising a valve stem 18 biased to an upper position by means of a spring 19, and provided with a winding 20 and an armature 21. When valve V¹ is energized, as shown in the drawings, valve stem 18 of this valve moves downwardly against the bias exerted by the associated spring 19, and under these conditions, a pipe 22 which communicates with pipe 17 is connected with atmosphere through a port 23, thus connecting the region of cylinder 9 between piston 10 and the upper end of the cylinder with atmosphere. When valve V¹ is deenergized, however, valve stem 18 of this valve is moved upwardly by spring 19, and pipe 22 is then disconnected from port 23, so that the region of cylinder 9 between piston 10 and the upper end of the cylinder is then disconnected from atmosphere. When valve V² is energized, valve stem 18 of this valve moves downwardly, and a pipe 24 which constantly communicates with the pipe 22 is then connected with a pipe 25 forming part of a low pressure distribution system. This low pressure distribution system is constantly supplied with fluid pressure, usually air, from a relatively low pressure source not shown in the drawings, and it follows that when valve V² is energized, the region of cylinder 9 between piston 10 and the upper end of the cylinder is supplied with fluid pressure from the low pressure system. When valve V² is deenergized, however, pipe 24 is disconnected from pipe 25, and is connected with a pipe 26 which leads to the valve V³. When valve V³ is energized, valve stem 18 of this valve moves downwardly, and pipe 26 is then connected with a pipe 27 forming part of a high pressure distribution system, which latter distribution system is constantly supplied with fluid pressure, usually air, from a relatively high pressure source. It will be seen, therefore, that when valve V³ is energized and valve V² is deenergized, the region of cylinder 9 between the piston 10 and the upper end of the cylinder is supplied with fluid pressure from the high pressure system. When valve V³ is deenergized, however, valve stem 18 of this valve moves to its upper position, and pipe 26 is then disconnected from pipe 27, so that the supply of fluid pressure from the high pressure system to cylinder 9 is cut off.

The pressure of the fluid in the low pressure system may be maintained at any suitable pressure, but for purposes of illustration, we will as-

sume that this pressure is maintained at approximately 50 pounds per square inch. Likewise, the pressure of the fluid in the high pressure system may be maintained at any desired pressure, but for purposes of illustration, we will assume that this pressure is maintained at approximately 100 pounds per square inch.

The valves V are controlled in part by two pressure responsive devices P²⁰⁻³⁰ and P⁷⁰⁻⁸⁰, each comprising a Bourdon tube 28 connected to the pipe 17, and hence subjected to the pressure of the fluid in the region of cylinder 9 between the piston 10 and the upper end of the cylinder. Each Bourdon tube 28 controls two contacts 29-29^a and 29-29^b. The pressure responsive devices P²⁰⁻³⁰ and P⁷⁰⁻⁸⁰ are so constructed that they will operate successively as the pressure of the fluid in the region of cylinder 9 between piston 10 and the upper end of the cylinder increases. For example, for all pressures below 20 pounds per square inch, contact 29-29^a of each of these devices is closed. If the pressure exceeds 20 pounds per square inch, however, contact 29-29^a of device P²⁰⁻³⁰ opens, and if the pressure exceeds 30 pounds per square inch, contact 29-29^b of device P²⁰⁻³⁰ closes. In similar manner, the pressure responsive device P⁷⁰⁻⁸⁰ is adjusted to open its contact 29-29^a at 70 pounds per square inch, and to close its contact 29-29^b at 80 pounds per square inch. Of course, these specific pressures are not essential, but are only mentioned for purposes of explanation.

The valves V are further controlled by means of two slow-releasing relays B and C of the usual type, and by a manually operable lever L, which lever also controls the relays B and C. As here shown, the lever L is capable of assuming five positions, indicated by dotted lines in the drawings, and designated by the reference characters p¹ to p⁵, inclusive. Operatively connected with the lever L are a plurality of contacts designated by the reference characters 30 to 36, inclusive, with exponents corresponding to the position, or positions, of the lever in which the associated contact is closed. For example, contact 30⁵ is closed in the p⁵ position of the lever. In similar manner, contact 33⁴⁻⁵ is closed in the p⁴ position of the lever, the p⁵ position, and any position intermediate these two positions.

Lever L will usually be located at a point remote from the braking apparatus, as in the control cabin of a classification yard car retarder system, and will be connected with the braking apparatus by means of line wires extending from the control cabin to the braking apparatus.

As shown in the drawings, lever L occupies its p¹ or "off" position. Under these conditions, a circuit is completed for relay C at contact 32¹⁻² of lever L, and current flows from a suitable source, such as a battery D, through wires 37, 38 and 39, contact 32¹⁻² of lever L, line wire 40, the winding of relay C, wire 41, and line wire 42 back to battery D. Relay C is therefore energized. All circuits for relay B are open, and this relay is accordingly deenergized. The valves V² and V³ are both deenergized, but valve V¹ is energized over a circuit which passes from battery D through wires 31, 38, 39, 43 and 44, contact 34¹ of lever L, line wire 45, back contact 46-46^a of relay B, wire 47, winding 20 of valve V¹, wires 48 and 49, and line wire 42 back to battery D. Since valves V² and V³ are both deenergized, the supply of fluid pressure to motor M from both the low and high pressure distribution systems is cut off, and since valve V¹ is energized the region of cyl-

inder ⁴ of motor M between piston ¹⁰ and the upper end of the cylinder is connected with atmosphere. The braking bars are therefore held in the ineffective or non-braking positions by gravity.

In explaining the operation of the apparatus as a whole, we will first assume that the operator wishes to make a comparatively light brake application. To do this he moves lever L to its ^{p²} position, thereby opening contact ^{34¹} of the lever and closing contact ^{36²}. The opening of contact ^{34¹} interrupts the circuit which was previously closed for valve V¹ at this contact, and valve V¹ therefore becomes deenergized and dis-

¹⁰ connects pipe 22 from pipe 23, thus disconnecting the region of cylinder 9 of motor M between piston ¹⁰ and the upper end of the cylinder from atmosphere. The closing of contact ^{36²} of lever L completes a circuit for valve V², and current flows from battery D through wires ^{31, 38, 39, 43,}

^{44, 50 and 51}, contact ^{36²} of lever L, line wire ⁵², contact ^{29-29^a} of pressure responsive device P²⁰⁻³⁰, wires ^{53, 54, 55 and 56}, winding ²⁰ of valve V², wire ⁴⁹, and line wire ⁴² back to battery D.

²⁵ Valve V² therefore becomes energized and connects pipe 24 with pipe 25, so that fluid pressure from the low pressure distribution system is now supplied to the upper end of cylinder 9 of motor M. The fluid pressure thus supplied to cylinder 9 forces piston ¹⁰ downwardly and cylinder 9 upwardly, thereby moving the braking bars toward their braking positions. As soon as the pressure in cylinder 9 increases to 20 pounds per

³⁰ square inch, contact ^{29-29^a} of pressure responsive device P²⁰⁻³⁰ opens and interrupts the circuit just traced for valve V². Valve V² then becomes deenergized and cuts off the supply of fluid pressure to cylinder 9 until the pressure in the cylinder has again decreased to 20 pounds per

³⁵ square inch, whereupon contact ^{29-29^b} again closes and reestablishes the circuit for valve V². If the pressure of the fluid in the upper end of cylinder 9 now increases to 30 pounds per square inch for any reason, contact ^{29-29^b} of pres-

⁴⁰ sure responsive device P²⁰⁻³⁰ will become closed and will complete another circuit for valve V¹, this latter circuit passing from battery D through wires ^{37, 38, 39, 43, 44, 50 and 51}, contact ^{36²} of lever L, line wire ⁵², contact ^{29-29^b} of pressure

⁴⁵ responsive device P²⁰⁻³⁰, wire ⁵⁷, back contact ^{46-46^a} of relay B, wire ⁴⁷, winding ²⁰ of valve V¹, wires ^{48 and 49}, and line wire ⁴² back to bat-

⁵⁰ tery D. Valve V¹ will therefore become energized and will vent fluid from the upper end of cylinder 9 to atmosphere until the pressure of the fluid in this region of the cylinder again decreases to 30 pounds per square inch, at which time contact ^{29-29^b} of pressure responsive device P²⁰⁻³⁰ will open and will deenergize valve V¹.

⁵⁵ It will be seen, therefore, that when lever L occupies its ^{p²} position, the braking bars will be held in their braking position by a pressure of be-

⁶⁰ tween 20 and 30 pounds per square inch.

⁶⁵ If the operator desires to make a more powerful brake application, he will move lever L to its ^{p³} position. This movement of the lever interrupts the circuit which was previously closed for the slow-releasing relay C at contact ^{32¹⁻²} of lever L, and as a result, as soon as a time in-

⁷⁰ terval equal to the release time of this relay has expired, this relay will release its armature, thus opening its front contact ^{58-58^a} and closing its back contact ^{58-58^b}. The operation of these contacts under these conditions, however, will

⁷⁵ have no effect on the remainder of the apparatus.

The movement of lever L to its ^{p³} position also interrupts all of the previously traced circuits for the valves V¹ and V², and completes another circuit for the valve V³, this latter circuit passing from battery D through wires ^{37 and 38}, contact ^{31³} of lever L, line wire ⁵⁹, wires ^{60 and 56}, winding ²⁰ of valve V³, wire ⁴⁹, and line wire ⁴² back to battery D. It will be noted that this latter circuit is controlled solely by contact ^{31³} of lever L, so that when this circuit becomes closed, it will remain closed as long as lever L remains in its ^{p³} position. When this circuit becomes closed, valve V³ will of course become energized, and will admit fluid from the low pressure distribution system to the upper end of cylinder 9 of motor M, and it follows, therefore, that when lever L occupies its ^{p³} position, the braking bars will be held in their braking position by the full pressure of the low pressure source.

If a still higher braking force is desired, the operator will move lever L to its ^{p⁴} position. When he does this, all circuits previously traced for the valves V¹ and V² will be interrupted, and if back contact ^{58-58^a} of relay C is then closed, as will be the case if the lever is moved to its ^{p⁴} position after remaining in its ^{p³} position long enough to cause relay C to release its armature, valve V³ will immediately become energized and will admit fluid pressure to the upper end of cylinder 9 of motor M from the high pressure system, the circuit for valve V³ under these conditions passing from battery D through wires ^{37, 38, 39, 43, 44 and 50}, contact ^{35⁴} of lever L, line wire ⁶¹, contact ^{29-29^a} of pressure responsive device P⁷⁰⁻⁸⁰, wire ⁶², back contact ^{58-58^b} of relay C, wire ⁶³, winding ²⁰ of valve V³, and line wire ⁴² back to battery D. If, however, when lever L is moved to its ^{p⁴} position, the armature of relay C is still picked up so that back contact ^{58-58^b} of this relay is open and front contact ^{58-58^a} is closed, as will be the case if the lever is moved to its ^{p⁴} position from its ^{p¹} or ^{p²} position without stopping the lever in its ^{p³} position, valve V³ will not become energized until relay C releases its armature and closes its back contact. Furthermore, under these latter conditions, as long as front contact ^{58-58^a} of relay C remains closed after lever L has reached its ^{p⁴} position, valve V² will be energized over a circuit which passes from battery D through wires ^{37, 38, 39, 43, 44 and 50}, contact ^{35⁴} of lever L, line wire ⁶¹, contact ^{29-29^a} of pressure responsive device P⁷⁰⁻⁸⁰, wire ⁶², front contact ^{58-58^a} of relay C, wires ^{60 and 56}, winding ²⁰ of valve V², wire ⁴⁹, and line wire ⁴² back to battery D. When valve V² becomes energized, fluid pressure from the low pressure distribution system will, of course, be admitted to cylinder 9 of motor M in the manner previously described. The parts are so proportioned and the release time of relay C is so adjusted that the time required for relay C to release its armature after lever L reaches its ^{p⁴} position under these latter conditions will be sufficiently long to insure that the pressure of the fluid in cylinder 9 of motor M will build up to substantially the full pressure of the low pressure system before valve V³ becomes energized and admits fluid to the motor from the high pressure system. When the pressure of the fluid in cylinder 9 now increases to 70 pounds per square inch, which, of course, cannot happen until after valve V³ has become energized, since, as was previously pointed out, the pressure of the fluid in the low pressure system will usually be maintained at approximately 50 pounds per square inch, con-

tact 29-29^a of pressure responsive device P⁷⁰⁻⁸⁰ will open and will interrupt the circuit just traced for valve V³, so that the supply of fluid pressure to motor M will then be cut off. If the pressure in the upper end of motor M subsequently again decreases below 70 pounds per square inch, the circuit for valve V³ will be reestablished at contact 29-29^a of pressure responsive device P⁷⁰⁻⁸⁰ and fluid will again be admitted to cylinder 9. Furthermore, if the pressure in the upper end of cylinder 9 now increases to 80 pounds per square inch for any reason, contact 29-29^b of pressure responsive device P⁷⁰⁻⁸⁰ will become closed, and will complete a circuit for valve V² passing from battery D through wires 37, 38, 39, 43, 44 and 50, contact 35^c of lever L, line wire 61, contact 29-29^b of pressure responsive device P⁷⁰⁻⁸⁰, wires 54, 55 and 56, winding 20 of valve V², wire 49, and line wire 42 back to battery D. Valve V² will therefore become energized, thus connecting pipe 24 with pipe 25, and since the pressure in the upper end of cylinder 9 of motor M will then be considerably above the pressure of the fluid in the low pressure system, fluid will be exhausted from the motor into the pipe 25. As soon as the pressure of the fluid again decreases to 80 pounds per square inch, contact 29-29^b of pressure responsive device P⁷⁰⁻⁸⁰ will open and will deenergize valve V². It will be apparent, therefore, that when lever L occupies its p⁴ position, the braking bars will be urged to their braking positions by a pressure of between 70 and 80 pounds per square inch. The closing of contact 33⁴⁻⁵ of lever L, when lever L is moved to its p⁴ position, completes a circuit for relay B which passes from battery D through wires 37, 38, 39 and 43, contact 33⁴⁻⁵ of lever L, line wire 64, winding of relay B, wires 65 and 41, and line wire 42 back to battery D. Relay B will therefore become energized, but the energization of this relay will have no effect on the apparatus unless lever B is subsequently moved to its p¹, p² or p³ position to decrease the pressure of the fluid supplied to the cylinder 9 of motor M, which operation will be described in detail hereinafter.

We will now assume that lever L occupies its p⁴ position, and that the operator moves it to its p⁵ position. Under these conditions, all circuits previously traced for the valves V² and V³ will become interrupted and another circuit for valve V³ will become closed, this latter circuit passing from battery D through wire 31, contact 30^c of lever L, line wire 66, back contact 58-58^b of relay C, wire 63, winding 20 of valve V³, and line wire 42 back to battery D. Valve V³ will therefore become energized and will subsequently remain energized as long as lever L remains in its p⁵ position. Fluid pressure from the high pressure system will therefore now be supplied to cylinder 9 of motor M, so that the braking bars will exert their maximum braking force.

If the operator, instead of moving lever L to its p⁵ position from its p⁴ position, moves it directly to its p⁵ position from its p¹ or p² position, the apparatus will then function in the same manner as when the lever was moved directly to its p⁴ position from its p¹ or p² position, up to the point where relay C releases its armature, whereupon valve V³ will then become energized over the previously traced circuit including contact 30^c of lever L and back contact 58-58^b of relay C.

We will next assume that the operator has moved lever L to its p⁵ position to cause the

braking bars to exert their maximum braking force, and that he now wishes to restore the braking bars to their ineffective or non-braking positions. He will therefore move lever L from its p⁵ to its p¹ or "off" position. When he does this, the circuit which was previously closed for valve V³ at contact 30^c of lever L will become interrupted, and valve V³ will therefore become deenergized and will disconnect cylinder 9 of motor M from pipe 27, so that the supply of fluid pressure from the high pressure system will then be cut off. Furthermore, when the operator moves lever L to its p¹ position, the circuit which was previously closed for relay B at contact 33⁴⁻⁵ of lever L will also become interrupted, and relay B will therefore become deenergized. Due, however, to the slow-releasing characteristics of this relay, this relay will not immediately release its armature, and during the time interval while the armature of this relay remains closed after the lever reaches its p¹ position a circuit will be closed for valve V² which circuit passes from battery D through wires 37, 38, 39, 43 and 44, contact 34^c of lever L, wire 45, front contact 46-46^b of relay B, wires 55 and 56, winding 20 of valve V², wire 49, and line wire 42 back to battery D. Valve V² will therefore become energized and will connect motor M with pipe 25, and since the pressure of the fluid in the motor will then be above that in pipe 25, fluid will be vented from the motor into the low pressure system. The parts are so proportioned that valve V² will remain energized under these conditions long enough to permit the pressure of the fluid in the motor to decrease to substantially the pressure of the fluid in the low pressure system, and it will be seen, therefore, that a large percentage of the fluid in the motor will be vented into the low pressure system for use at a later time. When relay B finally releases its armature, valve V² will, of course, become deenergized, and valve V¹ will then become energized over the previously described circuit including back contact 46-46^a of relay B and contact 34^c of lever L. When valve V¹ becomes energized, the remainder of the fluid in the motor will be vented to atmosphere, thus permitting the braking bars to return to their ineffective or non-braking positions. The movement of lever L to its p¹ position also completes the previously described circuit for relay C including contact 32¹⁻² of lever L, so that relay C now becomes energized. The energization of this relay under these conditions, however, has no effect on the remainder of the apparatus. When the braking bars reach their non-braking positions, all parts are restored to the positions in which they are shown in the drawings.

If the operator, instead of moving lever L from its p⁵ position to its p¹ position, moves the lever from its p⁵ to its p² position, valve V³ and relay B will both become deenergized in the manner just described, but under these conditions, during the interval of time required for relay B to release its armature and open its front contact after it becomes deenergized, valve V² will become energized over the previously described circuit for this relay including contact 36^c of lever L, contact 29-29^b of pressure responsive device P²⁰⁻³⁰, and front contact 46-46^b of relay B, and when relay B finally opens its front contact and closes its back contact, valve V¹ will then become energized over the previously described circuit for valve V¹ including contact 36^c of lever L, contact 29-29^b of pressure responsive device P²⁰⁻³⁰ and 75

- back contact 46-46^a of relay B. Valve V¹ will then remain energized until the pressure of the fluid in the motor decreases to 30 pounds per square inch. It will be seen, therefore, that under the conditions just described, the fluid in motor M will be vented into the low pressure distribution system until the pressure decreases to substantially the pressure of the low pressure system after which the fluid in the motor will be vented to atmosphere until the pressure decreases sufficiently to cause contact 29-29^b of pressure responsive device P²⁰⁻³⁰ to open and deenergize valve V¹, whereupon the pressure responsive device P²⁰⁻³⁰ will operate to energize valve V¹ or valve V² in the same manner as when lever L is moved to its p² position from its p¹ position.

While in the foregoing, we have described the operation of the apparatus for only a few of the possible movements of lever L, the operation of the apparatus for the remainder of the movements of lever L is similar to that which has already been described, and it is believed, therefore, that this operation will be understood from an inspection of the drawings and from the foregoing without the necessity for describing it in detail here.

It should be pointed out that with the apparatus constructed as shown in Fig. 1, the relays C and B may be located either at the control point or at the braking apparatus without materially affecting the circuits for the valves V¹, V² and V³, or the operation of the apparatus.

Referring now to Fig. 2, in the modified form of apparatus here shown, the relays C and B are intended to be located at the control point, and rectifiers have been provided to decrease the number of line wires required between the control point and the braking apparatus. With the apparatus arranged as here shown, two additional contacts 73^a and 71^a are required on the lever L, these contacts being closed in the p¹ and p² positions of the lever, respectively.

The operation of the apparatus shown in Fig. 2 is as follows: When lever L occupies its p¹ or "off" position, in which position it is shown in the drawings, valves V² and V³ are both deenergized, and valve V¹ is energized over a circuit which passes from battery D through wires 73, 74 and 75, contact 34^a of lever L, wires 76 and 77, back contact 46-46^a of relay B, wire 78, line wire 79, an asymmetric unit 80 in its low resistance direction, winding 20 of valve V¹, wires 81 and 82, line wire 83, and wires 84 and 85 back to battery D. Since valves V² and V³ are deenergized, the supply of fluid pressure to the upper end of cylinder 9 of motor M from both the high and low pressure distribution systems is cut off, and since valve V³ is energized, the upper end of cylinder 9 is connected with atmosphere at port 23. The braking bars A¹ and A² are therefore held in their ineffective or non-braking positions by gravity. Furthermore, since cylinder 9 is vented to atmosphere, the contacts 29-29^a of the pressure responsive devices P²⁰⁻³⁰ and P⁷⁰⁻⁸⁰ are both closed, and the contacts 29-29^b of the pressure responsive devices P²⁰⁻³⁰ and P⁷⁰⁻⁸⁰ are both open. Relay B is deenergized, but relay C is held energized over a circuit passing from a battery E through wire 85, winding of relay C, wire 86, contact 32¹⁻² of lever L, and wires 102 and 87 back to battery E.

We will now assume that the operator moves lever L from its p¹ to its p² position cause the braking bars of the braking apparatus to exert a comparatively light braking force. This move-

ment of the lever will interrupt the circuit which was previously closed for valve V¹ at contact 34^a of the lever, and valve V¹ will therefore become deenergized and will disconnect cylinder 9 of motor M from atmosphere. The movement of lever L to its p² position will also complete a circuit for valve V², which circuit may be traced from battery D through wires 73, 74 and 75, contact 36^a of lever L, wire 88, line wire 89, an asymmetric unit 91 in its low resistance direction, contact 29-29^a of pressure responsive device P²⁰⁻³⁰, wire 92, winding 20 of valve V², wire 82, line wire 83, and wires 84 and 85 back to battery D. Valve V² will therefore become energized and will admit fluid pressure from the low pressure system to the upper end of cylinder 9 of motor M, thus causing the braking bars to move to their braking positions. When the pressure of the fluid in cylinder 9 increases to 20 pounds per square inch, contact 29-29^a of pressure responsive device P²⁰⁻³⁰ will open and will deenergize valve V², thus cutting off the supply of fluid pressure to the car retarder operating motors. If the pressure of the fluid in cylinder 9 now increases to 30 pounds per square inch, contact 29-29^b of pressure responsive device P²⁰⁻³⁰ will become closed, and another circuit for valve V¹ will then be completed, this latter circuit passing from battery D through wires 73, 74 and 75, contact 36^a of lever L, wire 88, line wire 89, asymmetric unit 91 in its low resistance direction, contact 29-29^b of pressure responsive device P²⁰⁻³⁰, line wire 94, contact 71^a of lever L, wires 95 and 77, back contact 46-46^a of relay B, wire 78, line wire 79, asymmetric unit 80 in its low resistance direction, winding 20 of valve V¹, wires 81 and 82, line wire 83, and wires 84 and 85 back to battery D. Valve V¹ will therefore become energized and will vent fluid from cylinder 9 to atmosphere in the manner previously described. As soon as the pressure of the fluid in cylinder 9 again decreases below 30 pounds per square inch, contact 29-29^b of pressure responsive device P²⁰⁻³⁰ will become opened and will interrupt the circuit just traced for valve V¹, so that this valve will then become deenergized, thus preventing further escape of fluid from cylinder 9 to atmosphere. It will be apparent, therefore, that with the apparatus constructed as shown in Fig. 2 when lever L occupies its p² position, a pressure of between 20 and 30 pounds per square inch will be maintained in cylinder 9 of motor M in substantially the same manner as it is maintained between these two pressures when lever L occupies a corresponding position with the apparatus constructed as shown in Fig. 1.

We will next assume that the operator moves lever L from its p² to its p³ position to increase the braking force exerted by the braking bars. Under these conditions, the circuits previously traced for valves V¹ and V² including contact 36^a of lever L will both become interrupted at this contact, and valve V² will now become energized over another circuit which passes from battery D through wire 73, contact 31^a of lever L, wire 96, line wire 97, wire 92, winding 20 of valve V², wire 82, line wire 83, and wires 84 and 85 back to battery D. It will be noted that this circuit does not include any of the pressure responsive contacts, and it will be apparent therefore that valve V² will now remain energized as long as lever L remains in its p³ position, so that under these conditions fluid 75

from the low pressure source will constantly be supplied to cylinder 9 of motor M to hold the braking bars in their braking positions. The movement of lever L to its p^3 position will also 5 interrupt the circuit which was previously closed for relay C at contact 32¹⁻² of lever L, so that relay C will now become deenergized. The de-energization of this relay under these conditions, however, will have no effect on the remainder 10 of the braking apparatus.

We will next assume that the operator moves lever L from its p^3 to its p^4 position to cause the braking bars to exert a still higher braking force. This movement of lever L will interrupt 15 the circuit which was previously closed for valve V² at contact 31³ of lever L, and will complete a circuit for valve V³, which latter circuit passes from battery E through wires 85 and 84, line wire 83, winding 20 of valve V³, an asymmetric 20 unit 98 in its low resistance direction, line wire 19, wire 99, back contact 58-58^b of relay C, wire 90, contact 70⁴ of lever L, line wire 94, contact 29-29^a of pressure responsive device P⁷⁰⁻⁸⁰, an asymmetric unit 101 in its low resistance 25 direction, wire 89, contact 35⁴ of lever L, and wires 102 and 87 back to battery E. Valve V² will therefore become deenergized, and valve V³ will become energized, so that fluid pressure will now be supplied to cylinder 9 of motor M from 30 the high pressure system. Fluid pressure will continue to be supplied to cylinder 9 of motor M under these conditions until the pressure in the cylinder reaches 70 pounds per square inch, at which time contact 29-29^a of pressure responsive device P⁷⁰⁻⁸⁰ will become opened and 35 will interrupt the circuit just traced for valve V³. Valve V³ will then become deenergized, thus cutting off the supply of fluid pressure to cylinder 9. If the pressure in cylinder 9 now increases to 80 pounds per square inch for any reason, so that contact 29-29^b of pressure responsive device P⁷⁰⁻⁸⁰ becomes closed, another circuit for valve V² will become completed and current will flow from battery E through wires 85 and 84, 40 line wire 83, wire 82, winding 20 of valve V², wire 92, contact 29-29^b of pressure responsive device P⁷⁰⁻⁸⁰, asymmetric unit 101 in its low resistance direction, line wire 89, contact 35⁴ of lever L, and wires 102 and 87 back to battery E. Valve 45 V² will therefore become energized, and since the pressure of the fluid in cylinder 9 will then be above that in the pipe 25, fluid will be vented into this pipe until the pressure in cylinder 9 decreases sufficiently to cause contact 29-29^b to 50 open and deenergize valve V². It will be seen, therefore, that when lever L occupies its p^4 position, the fluid in the car retarder operating motors will be maintained at a pressure of between 55 70 and 80 pounds per square inch in substantially the same manner as when lever L in Fig. 1 occupied its p^4 position.

If the operator moves lever L from its p^4 to its p^5 position to cause the braking bars to exert their maximum braking force, valve V³ will become energized over a circuit which passes from battery E through wires 85 and 84, line wire 83, winding 20 of valve V³, asymmetric unit 98 in its low resistance direction, line wire 19, wire 99, back contact 58-58^b of relay C, wire 90, contact 70⁵ of lever L, and wire 87 back to battery E. Fluid pressure will therefore now be supplied to motor M from the high pressure system as long as lever L remains in its p^5 position, thus causing the braking bars to exert their maximum 75 braking force.

We will next assume that the parts are in the positions in which they are shown in the drawings, and that the operator desiring to make a comparatively heavy brake application, moves lever L directly from its p^1 to its p^4 position without stopping the lever in either of the two intermediate positions. Under these conditions, the circuit which is closed for valve V¹ at contact 34¹ of lever L when lever L occupies its p^1 position, will become opened, and valve V¹ will therefore 10 become deenergized and will disconnect cylinder 9 of motor M from atmosphere. Furthermore, the previously described circuit for relay C including contact 32¹⁻² of lever L will become opened, and the previously described circuit for relay B including contact 33⁴⁻⁵ of lever L will become closed, so that relay C will become deenergized and relay B will become energized in much 15 the same manner as was previously described under similar conditions in connection with the description of Fig. 1. Due to the slow-releasing characteristics of relay C, when this relay becomes deenergized, its armature will remain closed for a relatively long interval of time thereafter, and during this interval of time valve V² will be energized over a circuit which passes from battery E through wires 85 and 84, line wire 83, wire 82, winding 20 of valve V², wire 92, line wire 97, wire 98, front contact 58-58^a of relay C, wire 90, contact 70⁴ of lever L, line wire 94, contact 29-29^a of pressure responsive device P⁷⁰⁻⁸⁰, asymmetric unit 101 in its low resistance 20 direction, line wire 89, contact 35⁴ of lever L, and wires 102 and 87 back to battery E. When valve V² is energized, fluid from the low pressure system will, of course, be admitted to cylinder 9 of motor M, and as was previously pointed out in connection with Fig. 1, the parts are so proportioned that the time interval during which relay C will remain energized under these conditions 25 will be long enough to permit the pressure of the fluid in cylinder 9 to build up to substantially the pressure of the fluid in the low pressure system. When relay C finally releases its armature, the circuit for valve V² will be interrupted by 30 the opening of front contact 58-58^a of relay C and valve V³ will then become energized over the previously described circuit including back contact 58-58^b of relay C and contact 70⁴ of lever L. Fluid pressure will then be supplied to the 35 cylinder 9 of motor M from the high pressure system. It will be apparent, therefore, that under the conditions just described, fluid pressure will first be admitted to cylinder 9 from the low pressure system until the pressure of the fluid 40 in the cylinder builds up to substantially that of the low pressure system after which fluid from the high pressure system will be admitted to cylinder 9. After valve V³ once becomes energized, the apparatus will then operate in the same manner as it does after this valve becomes energized when lever L is moved from its p^3 to its p^4 position, and the description of the operation of the apparatus from this point on need not, 45 therefore, be repeated here.

If the operator instead of moving lever L directly from its p^1 to its p^4 position moves it directly from its p^1 to its p^5 position, the apparatus will function in the same manner as has just been described, up to the point where relay C releases its 50 armature, at which time valve V³ will then become energized and will subsequently remain energized over the previously described circuit for this valve including back contact 58-58^b of relay C and contact 30⁵ of lever L.

- We will now assume that the braking bars have been moved to the positions in which they exert their maximum braking force by moving lever L to its p^5 position, and that the operator 5 desiring to restore the braking bars to their non-braking position, moves lever L from its p^5 position to its p^1 position. Under these conditions, the circuit which is normally closed for valve V³ at contact 30^a of lever L when lever L 10 occupies its p^5 position will become interrupted at this contact, so that valve V³ will now become deenergized and will cut off the supply of fluid pressure from the high pressure system to cylinder 9 of motor M. Furthermore, the circuit 15 which is normally closed for relay B at contact 33^a-5 of lever L when lever L occupies its p^5 position will also become interrupted, so that this relay will now become deenergized. When this relay becomes deenergized, it will not release its 20 armature until after the release time for which the relay is adjusted has expired, and as long as the armature of relay B remains closed, a circuit will be completed for valve V² which passes from battery D through wires 73, 74 and 75, contact 25 34^a of lever L, wires 76 and 77, front contact 46-46^b of relay B, line wire 97, wire 92, winding 20 of valve V², wire 82, line wire 83, and wires 84 and 85 back to battery D. Valve V² will therefore become energized and will connect cylinder 9 30 of motor M with pipe 25, and since the pressure of the fluid in cylinder 9 will then be above that in pipe 25, fluid from cylinder 9 will be vented into this pipe. As was previously pointed out, the release time of relay B is so adjusted that 35 when valve V² becomes energized under these conditions, it will remain energized long enough to permit the pressure of the fluid in cylinder 9 to decrease to substantially that of the fluid in pipe 25. When relay B finally opens its armature, the 40 circuit just traced for valve V² will, of course, be interrupted at contact 46-46^b of relay B, so that this valve will become deenergized, and valve V¹ will then become energized over the previously described circuit for this valve including back contact 45 46-46^a of relay B and contact 34^a of lever L. The energization of valve V¹ will cause the remainder of the fluid in the cylinder 9 to be vented to atmosphere so that the braking bars will now return to their non-braking positions. The movement 50 of lever L to its p^1 position will also complete the circuit for relay C including contact 32^a-2 of lever L and relay C will therefore become energized. The energization of this relay under these conditions, however, will have no effect on the remainder of the apparatus. When the braking bars reach their full non-braking positions, all 55 parts will be restored to the positions in which they are shown in the drawings.
- If, after lever L has been moved to its p^5 position so that the braking bars are moved to the position in which they exert their maximum braking force, the operator moves lever L to its p^2 position, valve V³ and relay B will both become deenergized, and relay C will become energized, 60 in the manner just described in describing the operation of the apparatus when lever L is moved from its p^5 to its p^1 position. Under these latter conditions, however, during the interval of time required for relay B to release its armature after 65 the lever reaches its p^2 position, valve V² will become energized over a circuit which passes from battery D through wires 73, 74 and 75, contact 36^a of lever L, wire 88, line wire 89, asymmetric unit 91 in its low resistance direction, contact 70 75 29-29^b of pressure responsive device P²⁰⁻³⁰, line
- wire 94, contact 71^a of lever L, wires 95 and 77, front contact 46-46^b of relay B, line wire 97, wire 92, winding 20 of valve V², wire 82, line wire 83, and wires 84 and 85 back to battery D. The energization of valve V² will connect cylinder 9 of motor M with pipe 25, and since the pressure of the fluid in cylinder 9 will then be above that in pipe 25, fluid will be vented from cylinder 9 into pipe 25. When relay B finally releases its armature, valve V² will, of course, become deenergized, and valve V¹ will then become energized over a circuit which is the same as that just traced for valve V² up to wire 77, from which wire this latter circuit passes through contact 46-46^a of relay B, wire 78, line wire 79, asymmetric unit 89 in its low resistance direction, winding 20 of valve V¹, wires 81 and 82, line wire 83 and wires 84 and 85 back to battery D. After valve V¹ becomes energized, the apparatus will then function in the same manner as when lever L was moved from its p^1 to its p^2 position.
- The operation of the apparatus shown in Fig. 2 for any other movements of lever L not specifically described herein, will be understood from the foregoing and from an inspection of the drawings without further description.
- It will be seen from the foregoing that with either the form of apparatus shown in Fig. 1 or that shown in Fig. 2, when lever L is moved to its p^4 or p^5 position, valve V² or valve V³ will be 30 energized and will admit fluid from the low or the high pressure system according as the armature of relay C is then picked up or released. It will also be seen that relay C will be energized only when lever L occupies its p^1 35 or its p^2 position so that if lever L is moved quickly from either its p^1 or its p^2 position to its p^4 or p^5 position, relay C, due to its slow-releasing characteristics, will function to energize the valves V² and V³ in such manner that fluid will 40 first be admitted to the cylinder 9 of motor M from the low pressure system until the pressure of the fluid in cylinder 9 builds up to substantially that of the low pressure system, after which fluid from the high pressure system will be automatically admitted to cylinder 9. This effects 45 a considerable saving in the cost of the fluid required for the operation of the car retarder, since it costs less to compress fluid to a low pressure than it does to compress it to a high pressure. 50
- Likewise it will be noted from the foregoing, that if lever L is moved quickly from its p^4 or p^5 position to its p^1 or p^2 position, valve V² will first become energized and will connect motor M with pipe 25 long enough to permit the pressure of the fluid in the motor to decrease to substantially that of the low pressure system after which 55 valve V¹ will become energized and will vent fluid to atmosphere until the pressure of the fluid in the motor has been reduced to the proper pressure for the new position of the lever, the length of time the valve V² remains energized under these conditions being determined by the time required for relay B to release its armature. 60 This operation saves fluid which in a single pressure system would be wasted, thus effecting a further reduction in operating cost. 65
- One advantage of apparatus embodying our invention is that we effect the above described savings in fluid pressure by utilizing standard apparatus without the necessity for any special or complicated valves or other expensive parts.
- Although we have herein shown and described only two forms of railway braking apparatus em- 75

bodying our invention, it is understood that various changes and modifications may be made therein within the scope of the appended claims without departing from the spirit and scope of our invention.

Having thus described our invention, what we claim is:

1. Railway braking apparatus comprising a braking bar extending parallel to a track rail, a fluid pressure motor for moving said braking bar toward said track rail to a braking position, a first pipe connected with a source of relatively low pressure fluid, a second pipe connected with a source of relatively high pressure fluid, a slow-releasing relay, and means for at times supplying fluid pressure to said motor from said first or said second pipe according as the armature of said relay is picked up or released.

2. Railway braking apparatus comprising a braking bar extending parallel to a track rail, a fluid pressure motor for moving said braking bar toward said track rail to a braking position, a first pipe connected with a source of relatively low pressure fluid, a second pipe connected with a source of relatively high pressure fluid, a slow-releasing relay, manually controlled means for energizing said relay, means effective under certain conditions when said relay becomes deenergized for admitting fluid pressure to said motor from said first pipe during the time interval required for said relay to release its armature, and means effective after said relay has released its armature under such conditions for admitting fluid pressure to said motor from said second pipe.

3. Railway braking apparatus comprising a braking bar extending parallel to a track rail, a fluid pressure motor for moving said braking bar toward said track rail to a braking position, a first pipe connected with a source of relatively low pressure fluid, a second pipe connected with a source of relatively high pressure fluid, a manually operable lever having a plurality of positions each corresponding to a different braking force, a slow-releasing relay, means for energizing said relay when and only when said lever occupies a position corresponding to a low braking force, and means effective if said lever is moved quickly from the position in which said relay is energized to a position corresponding to a high braking force for supplying fluid to said motor from said first pipe during the time interval required for said relay to release its armature, and for subsequently supplying fluid to said motor from said second pipe.

4. Railway braking apparatus comprising a braking bar movable toward and away from a track rail into braking and non-braking positions and biased to a non-braking position, a first pipe connected with a source of relatively low pressure fluid, a second pipe connected with a source of relatively high pressure fluid, a first magnet valve effective when energized for connecting said motor with said first pipe, a second magnet valve effective when energized for connecting said motor with said second pipe, a slow-releasing relay, means for at times energizing said slow-releasing relay, and means at times effective when said relay becomes deenergized for energizing said first valve during the time interval required for said relay to release its armature and for subsequently energizing said second valve.

5. Railway braking apparatus comprising a braking bar movable toward and away from a

track rail into braking and non-braking positions and biased to a non-braking position, a first pipe connected with a source of relatively low pressure fluid, a second pipe connected with a source of relatively high pressure fluid, a first magnet valve effective when energized for connecting said motor with said first pipe, a second magnet valve effective when energized for connecting said motor with said second pipe, a manually operable lever having an "off" position and an "on" position in which said braking bar is adapted to exert a relatively high braking force, and a time element device controlled by said lever and effective when said lever is moved from its "off" to its "on" position for successively energizing said first and second magnet valves in such manner that fluid will be supplied to said fluid pressure motor from said first pipe until the pressure of the fluid in said motor builds up to substantially the pressure of the fluid in said first pipe after which fluid from said second pipe will be supplied to said motor.

6. Railway braking apparatus comprising a braking bar movable toward and away from a track rail into braking and non-braking positions, a fluid pressure motor for moving said braking bar to its braking positions, a first pipe connected with a source of relatively low pressure fluid, a second pipe connected with a source of relatively high pressure fluid, a first magnet valve for connecting said motor with said first pipe, a second magnet valve for connecting said motor with said second pipe, a lever movable to two different positions and having one contact which is closed in the one position and another contact which is closed in the other position, a relay provided with a circuit including one of said contacts, a circuit for said first magnet valve including the other contact of said lever and a front contact of said relay, and a circuit for said second magnet valve including said other contact of said lever and a back contact of said relay.

7. Railway braking apparatus comprising a braking bar movable toward and away from a track rail into braking and non-braking positions, a fluid pressure motor for moving said braking bar to its braking positions, a first pipe connected with a source of relatively low pressure fluid, a second pipe connected with a source of relatively high pressure fluid, a first magnet valve for connecting said motor with said first pipe, a second magnet valve for connecting said motor with said second pipe, a lever movable to two different positions and having one contact which is closed in the one position and another contact which is closed in the other position, a slow-releasing relay provided with a circuit including one of said contacts, a circuit for said first magnet valve including the other contact of said lever and a front contact of said relay, and a circuit for said second magnet valve including said other contact of said lever and a back contact of said relay.

8. Railway braking apparatus comprising a braking bar movable toward and away from a track rail into braking and non-braking positions, a fluid pressure motor for moving said braking bar to its braking positions, a first pipe connected with a source of relatively low pressure fluid, a second pipe connected with a source of relatively high pressure fluid, a first magnet valve for connecting said motor with said first pipe, a second magnet valve for connecting said motor with said second pipe, a lever movable to two different positions and having one contact

- which is closed in the one position and another contact which is closed in the other position, a relay provided with a circuit including one of said contacts, a pressure responsive device subjected to the pressure of the fluid in said fluid pressure motor and provided with a normally closed contact which becomes opened when the pressure of the fluid in said motor exceeds a predetermined value and with a normally open contact which becomes closed if the pressure of the fluid in said motor increases a predetermined amount beyond the pressure at which said normally closed contact becomes opened, a first circuit for said first magnet valve including the other contact of said lever, said normally closed contact of said pressure responsive device, and a front contact of said relay; a second circuit for said first magnet valve including the other contact of said lever and said normally open contact of said pressure responsive device; and a back contact of said relay.
9. Railway braking apparatus comprising a braking bar movable toward and away from a track rail into braking and non-braking positions and biased to a non-braking position, a fluid pressure motor for moving said braking bar to its braking position, a first pipe connected with a source of relatively low pressure fluid, a second pipe connected with a source of relatively high pressure fluid, means for at times supplying fluid to said motor from said first pipe and for at other times supplying fluid to said motor from said second pipe, a slow-releasing relay, manually controlled means for energizing said relay, and means effective under certain conditions when said relay becomes deenergized for exhausting fluid from said motor into said first pipe until said relay releases its armature and for subsequently exhausting fluid from said motor to atmosphere.
10. Railway braking apparatus comprising a braking bar movable toward and away from a track rail into braking and non-braking positions and biased to a non-braking position, a fluid pressure motor for moving said braking bar to its braking position, a first pipe connected with a source of relatively low pressure fluid, a second pipe connected with a source of relatively high pressure fluid, a first magnet valve effective when energized for connecting said motor with said first pipe, a second magnet valve effective when energized for connecting said motor with said second pipe, a third magnet valve effective when energized for connecting said motor with atmosphere, manually controlled means for selectively energizing said first and second valves to supply fluid to said motor, a time element device, and means controlled in part by said time element device and effective under certain conditions after said motor has been supplied with fluid from said second pipe for selectively energizing said second and third valves in such manner that fluid from said motor will be vented into said first pipe for a sufficient time interval to permit the pressure of the fluid in the motor to decrease a predetermined amount after which fluid will be vented to atmosphere.
11. Railway braking apparatus comprising a braking bar movable toward and away from a track rail into braking and non-braking positions and biased to a non-braking position, a fluid pressure motor for moving said braking bar to its braking position, a first pipe connected with a source of relatively low pressure fluid, a second pipe connected with a source of relatively high pressure fluid, a first magnet valve effective when energized for connecting said motor with said first pipe, a second magnet valve effective when energized for connecting said motor with said second pipe, a third magnet valve effective when energized for connecting said motor with atmosphere, manually controlled means for selectively energizing said first and second valves to supply fluid to said motor, a time element device, and means controlled in part by said time element device and effective under certain conditions after said motor has been supplied with fluid from said second pipe for selectively energizing said second and third valves in such manner that fluid from said motor will be vented into said first pipe for a sufficient time interval to permit the pressure of the fluid in the motor to decrease a predetermined amount after which fluid will be vented to atmosphere.
12. Railway braking apparatus comprising a braking bar movable toward and away from a track rail into braking and non-braking positions and biased to a non-braking position, a fluid pressure motor for moving said braking bar to its braking position, a first pipe connected with a source of relatively low pressure fluid, a second pipe connected with a source of relatively high pressure fluid, a first magnet valve effective when energized for connecting said motor with said first pipe, a second magnet valve effective when energized for connecting said motor with said second pipe, a third magnet valve effective when energized for connecting said motor with atmosphere, a lever having two positions and provided with a first contact which is closed in the one position and with a second and a third contact which are closed in the other position, a slow-releasing relay, a circuit for said slow-releasing relay including the second contact of said lever, a circuit for said first magnet valve including a front contact of said relay and said first contact, a circuit for said third magnet valve including a back contact of said relay and said first contact, and a circuit for said second magnet valve including said third contact.
